Fig. 2.

Figure 4: A side view of a mechanical assembly. It features a main housing 10 with a slot 12. A lever 14 is attached to a pin 16, which is part of a linkage system. A cylindrical component 18 is mounted on a shaft 20. Figure 5: A front view of the assembly, showing a housing 10 with a slot 12. A lever 14 is attached to a pin 16. A cylindrical component 18 is mounted on a shaft 20. The drawing includes several reference numerals such as 10, 12, 14, 16, 18, 20, 22, 24, 26, 28, 30, 32, 34, 36, 38, 40, 42, 44, 46, 48, 50, 52, 54, 56, 58, 60, 62, 64, 66, 68, 70, 72, 74, 76, 78, 80, STOCK SUPPLY AND REEL APPARATUS

Hubert E. Dickerman, Springfield, Mass.

Application April 1, 1947, Serial No. 738,696

1 Claim. (Cl. 242—54)

1

This invention relates to apparatus for supplying stock to machines consuming the stock.

The principal objects of the invention are the provision of stock supplying apparatus which is efficient in operation and so constructed and arranged as to be adapted to meet numerous and various conditions with facility.

It is well known to mount a coil or bundle of stock on a reel with the leading end thereof extending to a machine such as a press or the like which takes successive portions of the stock for various operations thereon. Such stock may be in the form of a strip, rod, wire or the like.

Such a machine as a press includes relatively reciprocating members and during the reciprocation thereof according to the prior art the stock is pulled from a coil on a reel by the press in an attempt to satisfy the requirements of successive portions of the stock. Invariably there is a tendency for the stock to be pulled to the extent that the reel overrides, operation is jerky and intermittent and the strip is likely to be loosely disposed around and about all of which and other disadvantages are objectionable.

According to this invention, apparatus is provided which includes a rotatable reel for supporting a coil which efficiently satisfies the requirements for stock by substantially continuous rotation thereby not only to avoid overriding and the resulting slackness but to obviate intermittent rotation and the consequent strains and jerks and provide the desired smoothness of operation and stock as it is required.

As special features of the invention, means is provided to check or stop the rotation of the reel when sufficient stock is provided the press. The apparatus is adapted for supplying stock from either the lower or upper side of a coil and in either of opposite directions thereby adapting the apparatus for use in connection with various machines and conditions. Rotative impulses are applied to the reel by means of resilient means thereby contributing to positiveness, smoothness and efficiency in operation regardless of the stroke timing of the press.

With the foregoing and various other novel features and advantages and other objects of my invention as will become more apparent as the description proceeds, the invention consists in certain novel features of construction and in the combination and arrangement of parts as will be hereinafter more particularly pointed out in the claim hereunto annexed and more fully described and referred to in connection with the accompanying drawings wherein;

2

Figs. 1 and 2 are front and rear elevational views respectively of the stock supply apparatus of the invention;

Fig. 3 is an elevational sectional view on the line 3—3 of Fig. 1; and

Figs. 4 and 5 are plan and side elevational views of the ratchet pawl construction of the apparatus.

Referring now to the drawings more in detail, the invention will be fully described.

10 A base 2 is provided which has a supporting upright 4 extending vertically therefrom. A bracket 6 is secured to the upright 4 and it has a transversely extending shaft or axle 8 secured thereto which projects forwardly therefrom. A reel hub member 10 is rotatable on the axle and spokes 12 have inner ends suitably secured to the hub and extend radially therefrom.

15 A rim 14 is secured to the outer ends of the spokes 12 and coil supporting arms 16 are slidable along the spokes and are secured thereto in desired positions of adjustment by means of set screws or the like, not shown. Guides 18 are adjustable along the members 16 and may be secured thereto in any position by means of set screws or the like, not shown. These members 18 extend radially relative to the axle 8. The hub, spokes, and members 16 and 18 constitute an adjustable reel and arms 16 which are parallel to the axle 8 are adapted to support and rotate a bundle or coil of stock.

20 A toothed ratchet wheel 20 is integral with the hub 10 and it will be obvious that as the ratchet wheel is urged in one direction or the other that the reel will be rotated thereby. The leading end of a strip of material from a coil on the arms 16 of the reel will be fed accordingly as the reel is rotated.

25 A pressure member 22 is reciprocable on the axle 8 and a friction member 24 is disposed between said member 22 and outer face of hub 10. A stud 26 has its inner end in threaded engagement with axle 8 and has fixed thereto a manually engageable member 28. A spring 30 is disposed between members 22 and 28. A collar 25 located rearwardly of hub is fixed to axle 8 and a friction member 27 is disposed between said member 25 and the rear face of said hub.

30 By adjusting the action of the spring 30 by means of the screw 26 and member 28 the desired amount of drag or braking effect may be applied to the reel hub. Thereby the rotation of the reel is resisted to any desired extent.

35 A double ended lever 34 is oscillatable on member 6 and relative to the axle 8 and a pawl 33 is pivoted thereon by means of a member 36.

A rod 40 is slidable in a tubular part 42 associated with the member 36. The rod 40 has its outer end threaded for adjusting nuts 44 and said rod may be connected to a machine such as a press, in such manner that it is reciprocated back and forth in the direction of arrows *a* and *b*. As the rod moves in the direction of arrow *a* the nuts 44 engage member 42 to swing lever 34 counterclockwise.

A spring 45 has its opposite ends connected to a rod 46 extending from the bracket 6 and to 35 at the upper end of lever 34 to urge said lever clockwise of Fig. 1. Hence, the rod 40 swings lever 34 counterclockwise against the action of spring 45. When rod 40 moves to the right spring 45 swings lever 34 clockwise so that the pawl 33 engages the ratchet wheel 20 to rotate it and the reel clockwise in direction of arrow *c* to supply stock. Thus rotative impulses are imparted to the reel by resilient means instead of by rod 40. The nuts 44 may be variously adjusted to provide the desired movement of lever 34.

It will be assumed that the convolutions of the coil C on the reel looking at Fig. 1 and represented by a circle are such that the leading end of the stock from the coil forms a loop which extends beneath a portion 48 of a control rod 51 and in the direction of the arrow *d*. It is desired that the rod 51 rest on and be supported by the loop of stock. Thus as the reel rotates clockwise stock is fed downwardly and around to the left to the machine which actuates the rod 40.

A double ended control lever 52 is oscillatable on axle 8 within member 6 and the rod 51 has its upper end pivotally connected thereto at its right hand end in Fig. 1. The lower portion of the rod 51 is slidable in a bracket 56 secured to the member 4 and said lever 52 on its upper side carries a guard plate 58 which is adapted as the lever 52 is swung clockwise in Fig. 1 to underlie the pawl 33 and prevent engagement thereof with the teeth of the ratchet wheel. As before, it will be assumed that the reel in Fig. 1 rotates clockwise in the direction indicated by arrow *c* to deliver stock so that it moves in the direction of arrow *d*. It will be noted that the relatively oscillatable components, as in Fig. 3, are arranged to provide a compact structure occupying but small space. The loop in the stock is disposed under the portion 48 of the rod 51 so that the rod is supported thereby and lever 52 is held in a position shown in Fig. 1 where the guard 58 is to the left of pawl 33.

As the stock on the reel runs out so that the loop of stock beneath rod 51 ceases to exert upward pressure thereto, the said rod descends whereby lever 52 swings clockwise so that the guard 58 underlies the pawl 33. Thereafter regardless of the movement of the rod 40 to swing the pawl carrying lever 34 and the actuating spring 45, the pawl is held out of engagement with the ratchet and the reel is not rotated. Thus the rod 51 and the lever 52 provide control means for the action of the ratchet operating means.

A bar 59 extends from the end of lever 52 (see Fig. 2) on which a weight 60 is adjustable. The weight is preferably adjusted so that the rod 50 is substantially counterbalanced. Therefore the lever 52 readily responds for its control function to the absence of the stock which normally exerts upward pressure to the rod 51.

Instead of the leading end of the stock from the reel extending clockwise and downwardly be-

neath the control rod it may extend counterclockwise upwardly and in the direction of arrow *e* to the machine. With this arrangement, as before, when the stock runs out so that the rod is no longer supported by the loop, the lever 52 swings to bring plate 58 between the pawl and ratchet wheel.

By providing the double ended levers 34 and 52, the parts may be interrelated to provide rotation of the reel to suit various conditions and various positions of the apparatus relative to a machine which is to be supplied with stock.

For instance, rod 40 may extend to the right from lever 34 and the spring 45 may exert its resilient impulse by being extended on the side of said lever opposite to that shown. And the rod 51 and weight bar 59 may be connected to ends of lever 52 from that shown to provide the control function. Or if desired, the rod 40 may be connected to the lower end of lever 34 and extend in either direction therefrom with the rod 51 and weight bar 59 appropriately connected to lever 52.

A specific arrangement of the components will depend on convenience and the conditions to be met, all within the scope of the invention.

The pawl 33 is provided with a lateral slot 62 and relatively angularly disposed flat faces 66 which are engaged by the end of a flat spring 68 which is secured to the end of lever 34. The construction is such that in a predetermined operating position of the pawl it may yieldingly pass over the teeth of the ratchet wheel when swinging in one direction while it will engage said teeth when swinging in operative direction. In an operating position, the pawl is limited in its movement to its ratchet engaging function while it may be shifted from one operating position to another.

It will be observed that the reel is adjustable to accommodate coils or bundles of stock of various sizes and that the stock may extend in various ways from the reel while the apparatus may be operated from a source located at either side thereof. The desired rotative impulse may be obtained irrespective of the length of stroke of the operating connection and at all times the rotating impulse is accomplished by resilient means which insures constant rotation of the reel at any desired magnitude and obviates jerks and starts and resulting overfeed and slackness of stock. The amount or rate of delivery of stock is not dependent on the stroke of the operating rod since the same is variable within adjustment of the components.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the appended claim are therefore intended to be embraced therein.

What it is desired to claim and secure by Letters Patent of the United States is:

Reel apparatus for supporting a coil of stock and supplying said stock in successive lengths comprising in combination, a support, an axle extending horizontally from said support, a reel means for a coil of stock rotatable on said axle having a ratchet wheel fixed thereto, an oper-

ating member swingable on said axle in operating and non-operating directions having a pawl pivoted thereon for engaging and swinging said ratchet when said member swings in operating direction, spring means connecting said support and operating member urging the latter in operating direction and means to swing said member in opposition to said spring means in non-operating direction, adjustable friction means between said reel means and support frictionally controlling rotation of the former relative to said axle, a control lever oscillatable on said axle between operating and non-operating position, an elongated member having an upper end pivoted to one end of said control lever and depending vertically therefrom and having a lower end portion for resting on the leading end of stock from a coil thereof on said reel means whereby said member is supported by said leading end of the stock to urge the control lever to operative position, and a guard plate carried by said control lever for disposition between said pawl and ratchet as said lever moves to non-operating position in the absence of stock supporting said elongated member.
